ASSIGNORS TO GENERAL ELECTRIC COMPANY, A CORPORATION OF NEW YORK.

MOTOR-CONTROL SYSTEM.

Application filed May 4, 1925, Serial No. 27,698. Renewed January 24, 1929.

Our invention relates to improvements in systems of motor control whereby a motor is started and stopped and generally controlled in a safe, reliable and efficient manner.

5 The invention has particular application to steel mill electric drives, although the invention is not necessarily limited to such an application. One of the requirements of an auxiliary drive in a steel mill is that the drive shall in no way delay the operation of the mill 10 of which it is a part. When the operator moves the handle of his master switch of the motor control system to a running position, the motor must start or, failing to start after 15 exerting the maximum possible starting torque within its capacity, it must be disconnected from the line. The motor must and will do its utmost, but it can do so without injury only when governed by the proper type of control 20 equipment. The control must permit the motor to go about its work with only normal effort, or in case of need, accelerate with the greatest power of which it is capable. The control must also provide that the motor shall 25 not be overtaxed, but having once done its utmost, shall be relieved of further effort which could only result in damage. Motor control systems operating on a function of the motor current have heretofore been used 30 to a considerable extent, and such systems have met with success where the load conditions are practically constant. However, if the loads are variable, the current limit control must be adjusted to meet the worst condition 35 such as for example, the condition encountered when a steel mill is first put into operation and before the parts have "limbered up". An adjustment for this value is frequently too high for the normal running conditions so that the current limit control if set 40 for the extreme conditions will be set for too high a value for the normal conditions and the time taken in accelerating the motor is less than is desirable.

45 Time limit control has been resorted to as a means for taking care of the above condition, but the previous time limit control arrangements with which we are familiar have left a great deal to be desired from the standpoint 50 of simplicity of construction and arrangement and general reliability and effectiveness of operation. Our invention is therefore directed particularly to improvements whereby a proper timing action is obtained between the 55 successive short-circuiting of sections of an

accelerating resistor in the motor armature circuit, whereby the timing action is obtained and the successive short-circuiting of the sections of the accelerating resistor is obtained by means of a simple, reliable and effective 60 device incorporated in a control system which is itself simple and effective.

In carrying our invention into effect, we preferably employ a time interval relay of the type disclosed and broadly claimed in an application of George B. Starie, Serial No. 125,112, filed July 26, 1926, which is a divisional application of the application of George B. Starie, Serial No. 28,036, filed May 4, 1925 (docket No. 33,328). The Starie time 70 limit relay comprises a magnetic structure with a winding thereon and a magnetic movable element or armature carrying a switch contact, the armature being biased to the unattracted position and the switch contact carried by the armature being biased to a definite position (in some cases the contact is biased to the closed position and in other cases the contact is biased to the open position as will be 75 hereinafter explained). The armature of the 80 electromagnetic device is biased to the unattracted position by suitable means such as a spring, the tension of which may be adjusted so that when the armature is in the attracted position, it is magnetically held in that position against the action of the spring tending to move the armature to the unattracted position. In accordance with our invention, the winding of the electromagnet is connected in 85 multiple relation with a section of the resistor in the motor armature circuit so that when this resistor is short-circuited, the winding will also be short-circuited. By reason of the fact that the winding has a considerable 90 inductive effect, the short-circuiting of the winding will permit the induced current to maintain a magnetic flux in the magnetic structure of the electromagnet and thus maintain the armature in the attracted position for 95 an appreciable interval of time. This time interval is employed for controlling the successive closings of a plurality of resistor switches 100 for short-circuiting the sections of the motor armature resistance in the desired succession.

105 As applied to a reversing control system in which the motor is "plugged" to effect a rapid reversal, the Starie electromagnetic switch or relay is employed to give a control of the motor in accordance with the value of the current in the motor armature circuit so that 110

the plugging resistor will be short-circuited very promptly after the closing of the directional contactors for the motor when the motor is initially connected to the supply circuit, but when the connections of the motor armature to the supply circuit are reversed to the source of supply to obtain a quick reversal by the well known plugging action, the electromagnetic device will delay the short-circuiting of the plugging resistor until after the motor armature has substantially stopped rotating.

The invention of the present application is an improvement of the system and apparatus 15 of our former application, Serial No. 527,520, filed January 6, 1922, a renewal of application, Serial No. 354,030 filed January 26, 1920, which discloses a system having broad 20 features of similarity to the system of the present application and which broadly claims the system and apparatus of the present application.

For a better understanding of the invention, reference is had to the accompanying 25 drawing, in which Fig. 1 is a very simplified diagram of a control system in accordance with the invention, Fig. 2 is a side view of the Starie electromagnetic switch employed by us in obtaining the desired time limit control 30 and the sequential action of shunting the accelerating resistance step by step in the motor armature circuit, and Fig. 3 is a front view of the switch.

Referring to the drawing, the motor is indicated as having an armature 10 and a series field 11, and this motor is arranged to be connected to the direct current source of supply 12 for either direction of operation by means of the pairs of reversing or directional contactors 13 and 14 for the forward direction 40 of motor operation and 15 and 16 for the reverse direction of motor operation. The protective resistance included in the motor armature circuit has a plurality of sections, the 45 section 17 being provided for controlling the plugging action and the sections 18 and 19 being provided for accelerating purposes. The resistor 17 is controlled by means of the plugging contactor 20 and the resistor sections 18 and 19 are respectively controlled by the contactors 21 and 22. The line contactor 23 is provided for completely disconnecting the motor from the source of supply 50 when a disconnecting switch is open.

The electromagnetic switches or relays 55 and 26 are provided for controlling the plugging resistor contactor 20 and the similar relays 27 and 28 are provided for controlling the accelerating resistor contactors 21 and 22 60 respectively. These contactors are under the control of the master switch or controller 24, as will be hereinafter set forth. It will be observed that the winding of the relay 27 is connected in multiple relation with the plugging resistor 17 and that the winding of the

relay 28 is connected in multiple relation with the plugging resistor 17 and the first accelerating resistor 18. This is for the purpose of obtaining a proper sequence in the action of the relays as will be hereinafter 70 fully explained.

The winding of the relay 25 is arranged to be connected across the motor armature 10 and the plugging resistor 17 for one direction of motor operation and the winding of 75 the relay 26 is similarly connected for the other direction of motor operation. It will be observed that these plugging relays 25 and 26 are normally open devices; that is, the switch contacts controlled by these relays are 80 biased to their open positions. Relays 27 and 28, on the other hand, are normally closed devices, since their controlling contacts are normally in the closed position with the winding 85 of the relay deenergized.

The relays 25 to 28 inclusive are preferably of identical construction with the exception that the contacts of the relays 25 and 26 are normally in their open positions, whereas the relays 27 and 28 have their contacts normally 90 in the closed position. Each of these relays is preferably of the construction shown in more detail in Fig. 2, which as before stated, discloses the construction claimed specifically 95 in the said Starie application. 95

Referring to Figs. 2 and 3, the electromagnetic switch or relay therein shown comprises a magnetic structure including the strap 29 of magnetic material and the core 30 of magnetic material on which the winding spool 31 is disposed. This magnetic structure is secured to the support 32 of insulating material by means of the bolt 33. Cooperating with the magnetic structure is a magnetic movable element or armature 34 which is biased to the un-attracted position by means of the spring 35, the force of which is adjusted by adjusting the nut 36 on the bolt 37 on which the spring 35 is mounted. The bolt 37 is supported in position and the armature 34 is supported in 100 position by means of the supporting member 38 which is secured to the strap 29 of the magnetic structure of the electromagnet, the armature having a knife edge bearing on the support 38. The armature 34 carries a switch 110 contact 39 at one end thereof, and this contact cooperates with a stationary but adjustable contact 40. The shim 41 of non-magnetic material is supported by the armature 34 and is arranged to make engagement with the end 115 of the core 30 of the electromagnet so as to provide a definite air gap between the armature 34 and the end of the core 30 when the armature is in the attracted position. The adjustable stationary contact 40 is carried by 120 a strap 42 which is secured to the insulating support 32 by means of the bolt 43. The winding 31 is provided with a sufficient number of turns so that with the armature in the 125 attracted position, the magnetic flux of the 130

electromagnet is considerably in excess of the value required to magnetically hold the armature in the attracted position. This is of advantage, since the timing action obtained by means of the relay will be substantially unaffected by variations in the voltage of the source of supply and variations of the heating of the winding.

As thus constructed and arranged, the operation of our invention is as follows: Assume that the disconnecting switches 44 and 45 are closed and that the various parts of the system are in their respective positions shown in the drawing, the closing of the disconnecting switch 45 in the control circuits with the master position in the "off" or neutral position as indicated in the drawing will cause the coil of line switch 23 to be energized to close through a circuit from the plus supply conductor, the segments 46 and 47 of the master controller 24, the coil of the line contactor 23 to the negative supply conductor. The closing of the line contactor 23 will produce no effect at this time, since the master controller is in the "off" or neutral position. The closing of the line contactor 23 will also effect the closing of the auxiliary switch 48 associated with this line contactor, and this will establish a maintaining circuit for the feed conductor to the segment 47 of the controller so that the controller may be moved out of the "off" position, thereby opening the circuit to the controller segment 46 and the line contactor will nevertheless be maintained closed.

35 If the master controller is now moved from the "off" position toward the left to its first operative position, the forward directional contactors 13 and 14 will be energized to close through a circuit from the plus supply conductor through the auxiliary switch 48, the segment 47 of the controller, segment 49 of the controller, through the coils of contactors 13 and 14 to the negative supply conductor. The winding of the relay 25 will be energized through the auxiliary switch 50 associated with the directional contactor 13 so that this winding will now be connected across the motor armature 10 and the plugging resistor 17. By reason of the fact that the motor is being started from rest, the motor armature will not have developed a counter electro-motive force until the motor starts so that as a practical matter the winding of the relay 25 will be energized by the drop in potential across the plugging resistor 17. This will be of a sufficient value so that the relay will be energized to close its contacts. This will produce no effect at the present time until the master controller 24 is thrown toward the left to its second operative position, but when the controller is thrown to that position, the plugging contactor 20 is energized to close immediately, the circuit for the coil of this contactor being from the plus supply conductor, the auxiliary switch 48 associated with the

line contactor 23, the segment 47 of the master controller, segment 49 of the controller, the contacts of relay 25, segments 51 and 52 of the master controller, through the coil of the plugging contactor 20 to the negative 70 supply conductor.

It will be observed that as soon as the motor is connected to the supply circuit, the windings of relays 27 and 28 are immediately energized to open their respective contacts. 75 This is because of the fact that the winding of relay 27 is energized in multiple relation with the plugging resistor 17 and the winding of relay 28 is energized in multiple relation with the accelerating resistor 18. Since 80 these relays are energized, the contacts controlled thereby are magnetically held in their respective open positions so that the resistor contactors 21 and 22 will not be energized until the proper interval in the starting of 85 the motor. When the plugging resistor contactor 20 closes its main contacts as previously described, it also short circuits the winding of the relay 27.

As before explained, the short-circuiting of the winding of this relay does not effect the immediate release of the relay armature, since it takes an appreciable interval of time for the flux in the magnetic structure of the relay to decrease due to the inductive action of the relay winding, and thus an appreciable interval of time elapses before the biasing spring of the relay armature overpowers the magnetic pull on the relay armature and effects the closing of the relay contacts. When the relay contacts close, the resistor contactor 21 is energized to close, provided the master controller 24 has been moved to the left to its third operative position, the circuit for the winding of this contactor being from the positive supply conductor, through the auxiliary switch 48 associated with the line contactor 23, the segments 47 and 49 of the master controller, the contacts of relay 25, segments 51 and 53 of the master controller, through the winding of the resistor contactor 21, the contacts of relay 27 to the negative supply conductor. The contactor 21 will thus be energized to close and short-circuit the accelerating resistor section 18 an interval of time after the short-circuiting of the plugging resistor 17.

The closing of the contactor 21 also short-circuits the winding of the relay 28 so that after an interval of time, the spring associated with the armature of relay 28 will overpower the magnetic attraction of the armature of the relay and the relay contacts will be permitted to assume their normal or closed position. The winding of contactor 22 is thus energized through a portion of the circuit previously traced by the winding of contactor 21, except that the winding of contactor 22 is connected to the negative supply conductor through the contacts of the relay 120

28. The resistor contactor 22 is thus energized to close and short-circuit the accelerating resistor section 19.

The motor is thus accelerated from rest to the full running speed and it will be observed that the contacts of the plugging relay 25 will be maintained in the closed position due to the fact that the coil of this relay is energized by the counter-electromotive force of the motor. Assume now that it is desired to reverse the motor quickly and employ the "plugging" feature of the control system. The master controller will be thrown from the full running position forward toward the right to an operative position for the reverse direction of motor operation. It is immaterial to which operative position the controller is thrown in so far as obtaining a quick reversal of the motor is concerned, but if the controller is thrown toward the right to the first operative position, the automatic progression of the closing of the resistor contactors will not be started. If the controller is thrown to the second reverse operative position, the automatic progression will be stopped when the resistor contactor 20 has been energized to close, but if the controller is thrown to the full running position reverse, the resistor contactors will all be energized to close in the previously mentioned succession so that the motor will be connected for full running speed in the reverse direction.

It will be assumed for the present explanation of the operation that the motor controller is thrown to the full running position reverse, since those skilled in the art will understand from the previous description the operation in case the master controller is arrested at an intermediate position. In such a case (full speed reverse), the resistor contactors 22 and 21 are first opened by reason of the fact that when the master controller leaves the third operative position forward, the circuit for the windings of these contactors is broken at the segment 53 of the controller. When the master controller leaves the second forward operative position, the plugging resistor contactor 20 is opened at the segment 52 of the master controller so that the resistance is all reinserted in the motor armature circuit before the reversing contactors 15 and 16 are energized to close in the first reverse position of the controller. The relays 27 and 28 are unaffected at this time by this operation of the master controller; that is, these relays are maintained in their closed position until after the master controller has been moved to the first reverse position.

When the master controller is moved to the first reverse position or to a succeeding reverse position, the winding of the relay 26 is connected across the motor armature and the plugging resistor 17 by the closing of the

auxiliary switch 54 associated with the directional contactor 16. However, by reason of the fact that the generated voltage of the motor armature is now in opposition to the voltage drop across the plugging resistor 17, the winding of relay 26 will not be sufficiently energized to close the relay until after the motor decreases in speed and until the motor has come practically to rest, so that the voltage drop across the resistor 17 will be of a sufficient value to energize this relay to close. The relay 26 is adjusted so that it will not be energized to close until after the motor has practically stopped rotating, at which time the beneficial effects of the plugging resistor are not needed and it is safe to shunt the plugging resistor and accelerate the motor for the reverse direction. This plugging resistor will ordinarily be of a substantially greater value than the resistors 18 and 19, because of the fact that this resistor is used to limit the current in the motor armature circuit during a critical condition of the motor during the plugging action.

When the relay 26 closes and provided the master controller is in its second operative position reverse, the plugging resistor contactor 20 is energized through a circuit from the positive supply conductor, through the auxiliary switch 48 associated with the line contactor 23, the segments 47 and 55 of the master controller, contacts of relay 26, the segment 56 of the master controller, through segment 57 of the master controller and the coil of the contactor 20 to the negative supply conductor. The relays 27 and 28 will have been energized to open when the directional contactors 15 and 16 closed after the opening of the directional contactors 13 and 14 for the forward direction of operation, so that the contacts of these relays will be successively closed in the manner previously explained in connection with the forward direction of motor operation.

It will be observed that the relays 25 and 28 inclusive may be of identical construction and characteristics, the sole difference being that with respect to the relays 25 and 26 they shall have normally open contacts, whereas relays 27 and 28 should have normally closed contacts.

It will be observed that we have provided a very simple and effective control system in which the acceleration of the motor is in accordance with a time interval action, a substantial time interval being provided between the successive shunting of the accelerating resistor sections due solely to the inductive effect or magnetic inertia of the flux in the magnetic structure of the relays 27 and 28. By reason of the fact that it takes an appreciable time interval for the flux of each of these relays to decrease to such a value that the holding effect thereof is overpowered by the biasing spring of the relay, the timing

action is obtained in a very simple and effective manner. If the time interval of operation of a particular relay is not of the desired value, the time interval may be adjusted by using a shim of different thickness than the shim 41. The time interval may also be adjusted by adjusting the nut 36 provided with each relay, thereby varying the spring tension against which the attractive force of the flux of the electromagnet has to operate in holding the relay contacts closed for an interval of time.

What we claim as new and desire to secure by Letters Patent of the United States, is:

1. In combination, two motor controlling resistors, a contactor for shunting the second of said resistors, and a single winding electromagnetic time element relay for controlling said contactor to control the shunting of the second resistor after the first resistor has been shunted, the said relay winding being connected in multiple relation with the first resistor so as to be shunted simultaneously with the shunting of the first resistor and delay the operation of the said resistor contactor to shunt the second resistor for an appreciable interval of time after the shunting of the first resistor due solely to the inductance of the relay.

2. A time interval motor control system comprising a plurality of resistors in the motor armature circuit for limiting the motor armature current, an electromagnetic time element switch for effecting the shunting of each of said resistors, each of said switches having a magnetic structure and a single winding for energizing the structure, and connections whereby the switches are caused to operate in a definite succession and each of said switches is caused to operate a substantial interval of time after a preceding switch of the succession has operated due solely to the magnetic inductance of the switch.

3. A time interval motor control system comprising a plurality of resistors connected in series relation in the motor armature circuit for limiting the motor armature current, a plurality of successively operated single winding electromagnetic time element switches for effecting the shunting of said resistors, the winding of each of said switches being connected to be energized responsive to the voltage drop of the resistor preceding the resistor controlled by the switch, and means whereby each of said switches is caused to operate to effect the shunting of the resistor controlled thereby a substantial time interval after the preceding resistor is shunted due solely to the inductive effect of the winding of the switch.

4. In combination in a motor control system, a plurality of resistors in the motor circuit arranged to be successively shunted, a contactor for shunting each of said resistors,

a single winding electromagnetic time element relay for controlling each of certain of said contactors, each of said relays having a magnetic structure, a winding permanently connected in multiple relation with a preceding resistor of the succession, a switch contact, an armature connected to said contact for operating the same and a spring for biasing the contact to the closed position and the armature to the unattracted position, the said winding being energized to move said armature to the attracted position and said contact to the open position until the preceding resistor is shunted and to then introduce a time interval in the closing of the relay directly in response to the inductance of said winding when the winding is shunted by the closing of the preceding contactor.

5. A motor control system comprising an accelerating resistor having a plurality of sections, a plurality of successively operated similar electromagnetic switches for controlling the successive short-circuiting of said sections, one of said switches being provided for each section of the resistor, each of said switches having a magnetic structure, a single winding connected in multiple relation with the resistor section preceding the section controlled by the switch for energizing said structure, a magnetic movable element carrying a switch contact, and a spring for biasing the said magnetic element to the unattracted position and the contact carried thereby to the closed position, the said winding being arranged to set up a magnetic flux in said structure considerably in excess of the value of flux required to hold the magnetic element in the attracted position, whereby upon the short-circuiting of the resistor section preceding the section controlled by the switch, the said winding is also short-circuited and the switch is magnetically held in the open position for an appreciable interval of time due only to the time required for the flux in said structure to decrease to a value that the said spring overpowers the magnetic holding effect on said magnetic element.

6. In combination, in a system of motor control, two motor controlling resistors, a contactor for shunting the second of said resistors, a time element single winding electromagnetic relay for controlling said contactor, the said relay having a magnetic movable member, a switch contact carried thereby and a spring which biases said member and contact to the closed position, the said winding being connected in multiple relation with the first of said resistors to set up a magnetic flux considerably in excess of the value required to hold said member in the attracted position and to be shunted with the shunting of said first resistor to release the said contact to close and energize said contactor to close a definite time thereafter determined by the time taken by said spring in overcom-

ing the magnetic pull on said member of the temporarily persisting flux of the relay.

7. A reversing motor control system comprising reversing switch mechanism for the motor, a "plugging" resistor and a plurality of accelerating resistors in the motor armature circuit, a contactor for shunting the said plugging resistor, a pair of similar normally open electromagnetic relays for controlling the said plugging contactor, one of said pair for each direction of motor operation, each of said relays having a winding, the winding of the plugging relay for controlling the plugging contactor for each selected direction of operation being connected across the motor armature and a portion of said resistors upon the closing of the reversing switch mechanism for the direction of motor operation selected, whereby the relay operates to effect the closing of the plugging contactor promptly when the motor is started from rest and only when the motor has practically stopped rotating when the motor is "plugged."
25. 8. A reversing motor control system comprising a "plugging" resistor and a plurality of accelerating resistors in the motor armature circuit, a contactor for shunting each of said resistors, a pair of relays governed in accordance with the motor armature current for governing the said plugging resistor contactor, an electromagnetic time element relay for governing each of said accelerating resistor contactors, and connections whereby the said time element relays operate in a predetermined sequence to govern the said accelerating contactors and each relay operates to give a substantial and practically unvarying time interval between the closing of the accelerating contactors after the closing of said plugging contactor due substantially entirely to the inductive effect of the relay winding.
9. A reversing motor control system comprising reversing switch mechanism, a plugging resistor and an accelerating resistor, a contactor for shunting each of said resistors, a pair of relays for controlling the plugging contactor, one of said relays for each direction of motor operation, the said relays having each a winding and normally open contacts and the winding of the relay operative for each selected direction of operation being connected across the motor armature and the plugging resistor upon the closing of said reversing switch mechanism for the direction of motor operation selected, whereby the relay operates to effect the closing of the plugging contactor promptly when the motor is started from rest and only when the motor has practically stopped rotating when the motor is "plugged," and a single winding time element relay for controlling the accelerating resistor contactor, the said accelerating relay having normally closed contacts and the winding of said accelerating relay being con-

nected in shunt relation with the plugging resistor so as to be energized to open the relay contacts promptly with the closing of the reversing switch mechanism and to be shunted with the shunting of the plugging resistor and delay the energization of the accelerating resistor for an interval of time determined solely by the inductance of the relay.

10. A reversing motor control system comprising reversing switch mechanism for the motor, a "plugging" resistor in the motor armature circuit, means responsive to the energization of the motor for shunting said plugging resistor immediately when the motor is started substantially from rest, but delaying the shunting of said resistor when the motor is plugged until a predetermined period in the plugging operation.

11. A reversing motor control system comprising a plugging resistor, means for shunting said plugging resistor, reversing switching mechanism, and control means responsive to a voltage drop in the motor circuit and the counter E. M. F. of the motor for controlling said shunting means so that said plugging resistor is shunted immediately when said switching mechanism is operated to close the motor circuit with the motor at rest, and is reinserted in the motor circuit when said switching mechanism is operated to the reverse running position for plugging whereupon said control means is held by the counter E. M. F. of the motor from again shunting said resistor until the motor is substantially at rest.

12. A reversing motor control system comprising a plugging resistor, a switch for controlling the starting and stopping of the motor for forward and reverse operation and the shunting of said plugging resistor, and control means responsive to a voltage drop in the motor circuit for controlling the shunting of said plugging resistor jointly with said switch whereby said plugging resistor is shunted immediately when said switch is thrown to a running position with the motor substantially at rest, said control means being responsive also to the counter E. M. F. of the motor so that when said plugging resistor is reinserted in the motor circuit by the throwing of said switch from a running position in one direction to a running position in the reverse direction said control means is held by the counter E. M. F. of the motor from again shunting said resistor until the motor has decelerated and is substantially at rest.

13. A reversing motor control system comprising reversing switch mechanism, a plugging resistor and an accelerating resistor, means responsive to the energization of said motor for shunting said plugging resistor immediately when the motor is started from rest, said means being responsive to the counter-electromotive force of the motor so that when the motor is plugged the shunting of the

plugging resistor is delayed until a predetermined period in the plugging operation, and electro-responsive switching means for shunting said accelerating resistor, said electro-
5 responsive switching means being provided with a winding connected across said plugging resistor.

14. A reversing motor control system comprising reversing switch mechanism, a plugging resistor and an accelerating resistor, electro-responsive switching mechanism actuated in response to the energization of the motor for shunting said plugging resistor immediately when the motor is started from

rest, said electro-responsive switching mechanism being responsive to the counter-electromotive force of the motor so that when the motor is plugged said plugging resistor is shunted only after the motor has been brought substantially to rest, and inductive time 20 switching mechanism controlled by said first switching mechanism for shunting said accelerating resistor.

In witness whereof we have hereunto set our hands this 2nd day of May, 1925.

EUGENE R. CARICHOFF.
